UNITED STATES PATENT OFFICE.

FREDERICK W. KENNEDY, OF SHELBYVILLE, INDIANA.

LINING FOR TRACTION-VEHICLES.

No. 818,257.

Specification of Letters Patent.

Patented April 17, 1906.

Application filed October 21, 1905. Serial No. 283,820

To all whom it may concern:

Be it known that I, FREDERICK W. KENNEDY, a citizen of the United States, residing at Shelbyville, in the county of Shelby and

5 State of Indiana, have invented certain new and useful Improvements in Linings for Traction-Vehicles; and I do hereby declare the following to be a full, clear, and exact description of the invention, such as will enable 10 others skilled in the art to which it appertains to make and use the same.

This invention relates to improvements in lining for traction-vehicles, and particularly to a sectional lining or bin for a car.

15 The object of the invention is the provision of means for facilitating the shipment of material in bulk—as, for instance, grain.

With this and other objects in view the invention consists of certain other novel constructions, combinations, and arrangements of parts, as will be hereinafter fully described, illustrated in the accompanying drawings, and more particularly pointed out in the claims hereto appended.

25 In the drawings, Figure 1 is a transverse sectional view of a railway-car provided with my improved lining. Fig. 2 is a perspective view of the adjustable sectional lining or bin. Fig. 3 is a perspective view of one of the sections of the lining.

Referring to the drawings, 1 designates the body of a vehicle, preferably a railway-car, within which is positioned a removable sectional lining, which comprises sections 2. 35 These sections are preferably manufactured from paper, either plain or crimped. The size of the sections may be varied at the option of the constructor for the purpose of conforming to the difference in the measurement of a car. The sections may be also constructed of cloth fabric, said sections to be secured together by sewing instead of gluing the overlapping portions, as may be done when employing paper sections to construct

45 the lining or bin in the car. The sections may be temporarily secured together by any suitable fastening means, so that they may be removed from a car and replaced in another car, if desired.

50 A box-car may be employed for shipping material in bulk—as, for instance, grain—by employing my sectional lining or bin. In some instances the lining may be employed to prevent leaks in cars while the loaded car is in transit.

Each section 2, Fig. 3, comprises a strip 3,

folded intermediate its length, as at 4, and upon the lower edge of said strip 3 there is formed a longitudinal flap 5, which normally lies in engagement with bottom piece 6, that is provided with a flap 7, which normally engages a portion of the side of the folded strip 3. It will therefore be apparent that by reason of the folded structure of the pieces constituting the sides and bottom of each section the edges of each section are reinforced by the flap 7 and a flap 7', of substantially the same size as that portion of strip 3 constituting the end of the section, thereby materially increasing the durability of the lining at that part which is liable to be subjected to the greatest amount of wear.

While I preferably construct the sections of paper or fabric, it will be obvious that the lining or bin may be formed of metal. The sections may be adjusted longitudinally or transversely for increasing or decreasing the size of the bin constituted thereby, as said sections preferably overlap at all of their engaging edges, Fig. 2.

What I claim is—

1. In a car, the combination with a body, of a lining positioned within said body, said lining reinforced upon its lower, outer edges. 2. In a car, the combination with the body, of a removable, sectional lining positioned within said body, each section of said lining reinforced upon its lower, outer edges. 3. In a car, the combination with a body, of a sectional lining positioned within said body, each section comprising a side strip folded intermediate its length, said strip provided with flaps upon its lower edge, a bottom strip engaging said flaps, said bottom strip provided with flaps upon its outer edges engaging the sides of said side strip.

4. In a car, the combination with a body, of a lining positioned within said body, said lining comprising overlapping sections, each section reinforced upon its lower, outer edge.

5. In a car, the combination with a body, of a lining comprising similarly-constructed, overlapping sections, positioned within said body, each section comprising a base, an end, and a side.

6. In a car, the combination with a body, of a lining carried by said body, said lining comprising similarly-constructed sections, each section comprising a base or bottom, and an end and a side secured to said bottom, said bottom of the same width as the height of said end and side.

7. In a car, the combination with a body, of a sectional lining carried by said body, each section of said lining comprising a bottom, a side, and an end, said side and bottom being of the same dimensions and of similar structure, whereby the side may be employed as the bottom when assembling the sections.
8. In a car, the combination with a body, of a lining carried by said body, said lining comprising overlapping, bodily-movable sections, each section comprising a base, an end, and a side.
9. In a car, the combination with a body, of a lining, constituting a bin, carried by said body, said lining comprising bodily-movable sections, each section comprising a bottom or base, an end, and a side.

10. In a car, the combination with a body, of a lining carried by said body, said lining comprising horizontally, bodily-movable sections. 20

11. In a car, the combination with a body, of a sectional lining, constituting a bin, carried by said body, each section comprising a bottom or base, a side, and an end, the bottom and side of the same dimension, whereby said bottom may be used as a side or vice versa. 25

In testimony whereof I affix my signature in presence of two witnesses.

FREDERICK W. KENNEDY.
